UNITED STATES PATENT OFFICE.

GEORGE A. MYERS, OF KALAMAZOO, MICHIGAN.

STREET OR STATION INDICATOR.

1,241,422.

Specification of Letters Patent. Patented Sept. 25, 1917.

Application filed April 3, 1916. Serial No. 88,544.

To all whom it may concern:

Be it known that I, GEORGE A. MYERS, a citizen of the United States, residing at Kalamazoo, in the county of Kalamazoo and 5 State of Michigan, have invented new and useful Improvements in Street or Station Indicators, of which the following is a specification.

This invention relates to improvements 10 in street or station indicators for use on street cars, interurban cars, railroad cars and other vehicles and has particular application to a manually operated indicator.

In carrying out the present invention, it 15 is my purpose to provide a street or station indicator whereby the names of the streets or stations may be displayed one after the other as the car approaches the same so as to advise the passengers of the names of 20 such streets or stations.

It is also my purpose to provide apparatus of the class described which will embody in its construction, among other features, two drums carrying a web having the 25 names of the streets or stations printed thereon, and means for rotating the drums in either direction so as to display the names of the streets or stations successively, in combination with means for compensating 30 for the relative changes in diameter of the drums incident to the winding and unwinding of the web thereon, whereby the names of the streets or stations will be properly displayed.

35 With the above and other objects in view, the invention consists in the construction, combination and arrangement of parts hereinafter set forth in and falling within the scope of the claims.

40 In the accompanying drawings;

Figure 1 is a view in front elevation of a street or station indicator constructed in accordance with the present invention.

Fig. 2 is a vertical sectional view there- 45 through, on the line 2—2 of Fig. 1.

Fig. 3 is a similar view on the line 3—3 of Fig. 1.

Fig. 4 is a vertical sectional view taken on line 4—4 of Fig. 2.

50 Referring now to the drawings in detail, 1 designates a substantially rectangular casing having the front wall formed centrally with a transverse sight opening 2 and arranged within the sight opening 2 is a panel of glass or other transparent material. Arranged within the casing 1 ad-

jacent to one end wall thereof is a vertical supporting wall 3 and journaled in horizontally alining bearings carried by the supporting wall 3 and the remote end wall are 60 shafts 4, 4 arranged adjacent to the top and bottom walls of the casing and in proximity to the front wall above and below the sight opening therein and fixed upon the shafts 4, 4 are drums 5, 5. In the supporting wall 65 3 and the remote end wall at a point behind and above the top drum 5 are rearwardly and upwardly inclined slots 6 alining with each other and also formed in such supporting wall and the remote end wall at a point 70 behind and above the lower drum 5 are upwardly and rearwardly inclined alining slots 7. Mounted in the upper slots 6 are the trunnions of a horizontal shaft 8 extending across the casing and normally disposed at 75 the lower ends of the slots, while mounted in the lower slots 7 are the trunnions of a horizontal shaft 9 extending across the casing. On the shafts 8 and 9 are relatively small drums 10 and 11 respectively bearing against 80 the respective drums 5, 5 so that upon the rotation of the drums 5, 5 similar but reversed motion will be imparted to the drums 10 and 11. 12 designates a web of paper or the like having the upper end portion secured to and wrapped about the top drum 10 and the other end portion carried downwardly over the upper drum 5, then around the lower drum 5 and secured to and wrapped about the lower drum 11. Ar- 85 ranged across the space between the supporting wall 3 and the remote end of the casing at a point between the drums 5, 5 is a strip 13 standing behind the sight opening 2 and designed to form a back for the 90 95 adjacent portion of the web.

The names of the streets or stations are printed on the web 12 and these names are spaced apart equal distances and when the lower drum 5 is revolved in the direction 100 of the arrow, the drum 11 is rotated incident to the frictional contact between the drums 5 and 11 and in this movement of the drums 5 and 11 the web is wound onto the drum 11 and off of the drum 10. On the 105 other hand, when the upper drum 5 is rotated in the direction of the arrow adjacent it, that is, in a direction opposite from the lower drum 5, the upper drum 10 is rotated incident to the frictional contact between such drums and the web 12 wound upon the drum 10 and off of the drum 11. 110

As the web winds on the drum 11 and off of the drum 10, the trunnions of the shaft 9 rise in the oblique slotted bearing's 7 so that the drum 11 moves away from the drum 5, 5 incident to the increased diameter of the drum 11, while the drum 10 moves downwardly toward the upper drum 5, incident to the decrease in diameter of such drum 10. Conversely when the web is wound onto the 10 drum 10, the latter moves away from the upper drum 5, while the lower drum 11 moves toward the corresponding drum 5. By means of this construction, it will be seen that the drums 10 and 11 gravitate toward the other drums and act as brakes to 15 keep the web always taut; and, as the web is moved, the names on the web will be at all times brought into proper position behind the sight opening irrespective of the 20 relative change in diameter in the drums 10 and 11.

Keyed upon the ends of the shafts 4 between the supporting wall 3 and the adjacent end wall of the casing 1 are ratchet 25 wheels 14, 14 respectively and formed in the outer surface of the supporting wall 3 between the ratchet wheels is a horizontal guideway 15. Slidably mounted within the guideway 15 is a block 16 and secured to one 30 end of the block 16 is a stem 17 projecting through an opening 18 formed in the front wall of the casing, while secured to the rear end of the block is one end of a coiled retractile spring 19, such spring having the 35 remaining end thereof fastened to the back wall of the casing. This spring 19 acts to hold the block 16 normally at the rear end of the guideway 15 and to restore the block to such position after the block has been moved 40 against the action of the spring and released. Pivoted between its ends upon the block 16 is a lever 20 having one end formed with a dog 21 adapted to engage the lower ratchet wheel 14, and the other end formed with a 45 boss 22; while pivoted upon the block between its ends is a second lever 23 having one end formed with a dog 24 adapted to engage the upper ratchet wheel 14 and the other end formed with a boss 25 to which 50 is connected a weighted arm 26 acting normally to hold the dog end of the lever 24 elevated to engage the teeth of the upper ratchet wheel 14. Also pivoted upon the block 16 between the boss ends of the levers 55 20 and 23 is a cam 27 capable of movement to engage the boss end of either lever to move the latter to inactive position so as to disengage the dog end thereof from the corresponding ratchet wheel.

60 The teeth on each ratchet wheel 14 are spaced apart distances equal to the spaces between the names of the streets or stations on the web. When the cam 27 is turned to swing the lower lever to inactive position, 65 the weighted arm 26 on the upper lever acts

to throw the last-named lever to active position to engage the dog end thereof with the upper ratchet wheel so that each time that the block 16 is pulled against the action of the spring 19 the web will be advanced a space to move one name out of the sight opening and the following name into such opening, while when the cam is turned in the other direction, the lower lever will be permitted to gravitate into engagement with the corresponding ratchet wheel, while the upper lever will be swung to inactive position so that each time that the block 16 is moved against the action of the spring 19 the weight will be advanced a step in the other direction. 70 75 80

In the present instance, one end of a cord 28 is connected with the outer end of the stem 17 so that the block may be actuated conveniently, while secured to the front wall 85 of the casing 1 is a bell 29 and pivoted to such wall is a hammer 30 adapted to strike the bell and under the control of a pin 31 on the stem 17. Each time that the stem is drawn into the casing under the action of the spring 19, the pin 31 strikes the hammer 30 so as to sound the bell. 90 95

While I have herein shown and described the preferred form of my invention by way of illustration, I wish it to be understood 95 that I do not limit or confine myself to the precise details of construction herein described and delineated, as modification and variation may be made within the scope of the claims and without departing from the 100 spirit of the invention.

I claim:

1. In an indicator of the class described, the combination with a transverse strip having an upright face, drums near the upper and lower edges of said strip, and a casing inclosing said elements and having a sight opening forward of the strip, bearings for the shafts of said drums, and slotted bearings inclined respectively toward those for said shafts, of weighted drums whose trunnions are mounted in said slotted bearings so that both these drums normally gravitate into contact with the others, a web wound on the drums and passing over the first-named drums and across the face of said strip, the web being provided with equally spaced indications on its front face, and means for selectively turning either of the first-named drums to draw the web 115 across said strip in steps corresponding with the spacing of its indications. 110 115 120

2. In an indicator of the class described, the combination with superposed drums having ratchet wheels fast on their shafts, 125 a casing in which the latter are journaled and having an opening between the drums and a guideway opposite said opening, and a web movable over the drums and past said opening and bearing indications at spaced 130

points on its face; of a manually operable block slidably mounted in said guideway, levers pivoted between their ends to said block and each having a dog on its long arm for engaging one of said ratchet wheels, a weight on the short arm of the upper lever whereby its dog is held normally in said engagement, the dog of the lower lever being held normally in such engagement by its own gravity, and a cam pivoted to the block between the short arms of the levers and adapted to be turned into contact with either so as to hold its dog out of engagement with the ratchet wheel, for the purpose set forth.

15 3. In a device of the class described, the combination with rotary elements mounted one above the other and having ratchet wheels on their shafts, a manually reciprocal member mounted to move between said 20 elements on a line at right angles to a line through their axes, and levers pivoted be-

tween their ends to said member and each having a boss on its short arm and a dog on its long arm to engage the teeth of one of the ratchet wheels; of a weighted arm connected to the boss of the upper lever to hold its dog normally in such engagement, the dog of the lower lever maintaining such engagement by its own gravity, and a cam movably mounted on said member between the bosses and capable of being set into contact with either so as to swing its dog out of such engagement, while permitting the dog of the other lever to maintain such engagement, for the purpose set forth. 35

In testimony whereof I affix my signature in presence of two witnesses.

GEORGE A. MYERS.
